UNITED STATES PATENT OFFICE.

HARRIS B. HOLT, OF DORMONT, PENNSYLVANIA.

TRAVELING GRATE.

Application filed January 19, 1924. Serial No. 687,249.

To all whom it may concern:

Be it known that I, HARRIS B. HOLT, residing at Dormont, in the county of Allegheny and State of Pennsylvania, a citizen 5 of the United States, have invented or discovered certain new and useful Improvements in Traveling Grates, of which improvements the following is a specification.

My invention relates to improvements in 10 the structure of traveling grates, and particularly traveling grates of the endless chain type, whereon fuel is continuously supplied to the combustion chamber of a furnace, and whereon the in-brought fuel is 15 within the combustion chamber continuously consumed.

I have developed my invention in application to a chain grate of the particular form shown in Letters Patent of the United 20 States No. 1,476,337, granted me on December 4th, 1923, and in that application I shall now show and describe it.

The structure in which my invention is found is illustrated in the accompanying 25 drawings. Figure I is a fragmentary view in plan from above (certain details appearing in horizontal section) of the grate structure. Figure II is a view in vertical and longitudinal section, showing a portion 30 of the grate structure in its assembly with the pulley which sustains it. Figure III is a detail view to larger scale, showing in side elevation the component elements of the 35 grate structure in articulation together. Figure IV is a view in vertical and transverse section on the plane indicated by the broken line IV-IV, Figure III. Figure V is a view of the grate bar assembly seen in end elevation and transverse section, on 40 the broken line V-V, Figure III.

The grate here shown is the grate of my patent referred to above, in that it consists 45 of a belt made up of a plurality of identical links assembled in rows and in echelon formation and articulated on rods threaded through eyes with which the links at their opposite ends are provided. Each link is formed medially with a T-shaped extension and in the assembly these T-shaped extensions come into alignment and form across 50 the grate structure substantially continuous supports for grate bars. Upon these supports so constituted the grate bars themselves are strung. The links are in the drawings indicated by the reference numeral 1. The rods upon which the rows of

links in echelon formation are pivotally united are indicated at 2. 3 are the T-shaped extensions upon the links, and 4 are the grate bars which are strung in rows 60 upon the supports constituted by these T-shaped extensions.

So far as concerns ventilation through the assembled links, the structure is the same as that of my patent and will be understood 65 on considering Figure IV of the drawings. As there appears, the grate bars are, intermediate their length, spaced apart. Terminaly however the square ends of the 70 grate bars when assembled present substantially continuous surfaces transversely of the grate. This particularly appears in Figure V.

My present invention is found in provision of such a grate as I have indicated 75 with means for catching the ashes as the grate at its forward end rounds the sprocket wheels or pulleys which carry and propel it,—means which prevent the ashes from falling through to foul and clog the structure and which insure the eventual discharge of the ashes in a direction not through the structure but from the place of lodgment outwardly and away from the structure as a 80 whole.

Referring particularly to Figure II of the drawings the endless grate structure is there shown to be carried at its forward end upon a pulley 5 which pulley is mounted on a shaft 6. At the opposite end it will be 85 understood that this grate structure is supported on and driven by sprocket wheels. It will be understood that in place of the pulley 5, sprocket wheels might be provided at this end of the grate also. The 90 direction of movement is in Figure II indicated by an arrow, and it will be perceived that whereas along the level upper course the grate-bars stand end to end in close array, with narrow intervals between, as 95 they round the pulley spaces *s* open between the ends of the bars. Into these spaces ashes necessarily fall and the object which I have in view is to prevent the ashes which fall 100 into these spaces from passing through and filling and clogging the spaces between the links and beneath and between the grate bars.

The grate bars shaped and mounted as already described are additionally provided 110 with forward extending aprons 41, and these aprons like the end walls of the grate bars

extend in substantial continuity transversely of the grate and form in the assembly continuous shelves transversely of the grate. As best seen in Figure III these forward extending aprons 41 which are formed upon the grate bars 4 are shaped to be substantially concentric, when the parts are assembled, with the center of pivoting of the links one upon another. It is apparent on considering Figure II that as the grate rounds the pulley 5, spaces *s* approximately V-shaped in cross-section open between successive rows of grate bars; and with the fact in mind that the forward extending apron-like projections upon the individual grate bars are concentric with the pivots which unite the chain links, it will be perceived that these apron-like projections close the approximately V-shaped spaces below and constitute bottoms of the pockets which so open as the structure rounds the pulley. Into these pockets some ashes necessarily fall, and in them the ashes are retained and prevented from falling through to foul the structure. In the further travel of the grate these pockets, initially right side up, are inverted, and they then discharge their contents by gravity, but they then discharge their contents outwardly, in a direction away from the grate structure.

Since the grate bars are square-ended, throughout the fuel supporting reach of the grate these square ends of successive rows of grate bars stand opposite one another, and the space between may in the designing of the grate be reduced to negligible width. It is only when in operation the structure rounds the pulley that the spaces open, and then the ashes which fall are caught and discharged in the manner already described.

It will be perceived that as this grate structure rounds the curved end of its path of travel the spaces which open are closed-bottomed. There is escape for the ashes from these pockets, neither forwardly nor rearwardly. Furthermore, this grate has an advantage which requires an additional word of explanation. It happens that if

grates of this sort are not properly attended to, discharged ashes will accumulate in a heap beneath the grate, and the grate, continuing to operate, must plow through the top of the accumulated heap. My grate with the approximately V-shaped spaces which I have now specified, even though it has to plow through such a heap, will not pick up ashes, and will not in its operation crowd ashes into the spaces within, and there will be no fouling, even though the ashes are allowed to accumulate in the manner described.

It sometimes is necessary in making repairs upon a grate to reverse its travel. In such circumstances the fact that the V-shaped spaces are closed rearwardly, that is to say, at the point where the apron 41 springs from the body of the grate bar 4, is a matter of great advantage, because under such conditions green coal, instead of falling through to clog the structure, merely rests in the pockets, from which it will either discharge itself or from which the attendant may easily remove it.

I claim as my invention:

In an endless chain-grate structure traveling in a curved-ended path the combination of a belt formed of interpivoted links, grate-bars borne by said belt, said grate-bars being arranged in rows, the grate-bars individually being square ended, and being provided with terminal aprons extending when the grate-bars are in place concentrically with the axes of pivoting of the sustaining links, said aprons cooperating with the square ends of the grate-bars to form closed-bottomed approximately V-shaped pockets which, closed throughout the level reaches, open as the structure traverses the curved end portions of its pathway.

In testimony whereof I have hereunto set my hand.

HARRIS B. HOLT.
